UNITED STATES PATENT OFFICE

SOLOMON FORMAN, OF NEW YORK, N. Y.

DESIGN FOR A COMBINED CASSEROLE AND COVER OR SIMILAR ARTICLE

Application filed October 29, 1930. Serial No. 37,434. Term of patent 7 years.

To all whom it may concern:

Be it known that SOLOMON FORMAN, citizen of the United States, and resident of New York city, in the county of New York and State of New York, has invented a new, original, and ornamental Design for Combined Casserole and Cover or Similar Article, of which the following is a specification, reference being had to the accompanying drawing, forming part thereof, in which—

Fig. 1 is a top plan view of a casserole embodying my new design; and
Fig. 2 is a side elevational view thereof.

I claim:

The ornamental design for a combined casserole and cover or similar article, substantially as shown.

Dated, October 28, 1930.

SOLOMON FORMAN.
